R. F. HOBBS

WALL PAPER

Filed Feb. 2, 1925

INVENTOR

Robert F. Hobbs
BY Kenyon & Kenyon

ATTORNEY

UNITED STATES PATENT OFFICE.

ROBERT F. HOBBS, OF DELANCO, NEW JERSEY, ASSIGNOR TO ROBERT F. HOBBS, INC.,
A CORPORATION OF NEW JERSEY.

DESIGN FOR WALL PAPER.

Application filed February 2, 1925. Serial No. 12,235. Term of patent 3½ years.

To all whom it may concern:

Be it known that I, ROBERT F. HOBBS, a citizen of the United States, residing at Delanco, in the county of Burlington and State of New Jersey, have invented a new, original, and ornamental Design for Wall Paper, of which the following is a specification, reference being had to the accompanying drawing forming a part thereof.

The figure in the drawing is a view of wall paper, showing my new design thereon.

I claim:

The ornamental design for wall paper as shown.

ROBERT F. HOBBS.
